TERMINAL FOR RAIL BONDS

Filed May 6, 1926

UNITED STATES PATENT OFFICE

WILLIAM B. WARDROP, OF BARNESBORO, PENNSYLVANIA

TERMINAL FOR RAIL BONDS

Application filed May 6, 1926. Serial No. 107,236.

This invention relates to terminals for rail bonds and more particularly to a terminal so constructed that it is readily recoverable, thus rendering it especially applicable in light gauge railways of mines where the rails must be constantly shifted and where accordingly ordinary rail bonds rapidly deteriorate and become useless.

A more specific object of the invention is to provide a split rail bond terminal having means whereby it may be expanded to fit an opening formed in the rail bond, the terminal being so formed that it may be alternately expanded and contracted for a great number of times before any tendency to breakage occurs.

These and other objects I attain by the construction shown in the accompanying drawing, wherein for the purpose of illustration is shown a preferred embodiment of my invention and wherein:

Figure 1 is a side elevation of adjoining rail sections connected by a bond constructed in accordance with my invention;

Figure 2 is an enlarged longitudinal sectional view therethrough taken on the line 2—2 of Figure 1;

Figure 3 is an enlarged sectional view on the line 3—3 of Figure 1;

Figure 4 is a side elevation of the terminal removed;

Figure 5 is an inner face of the terminal.

Referring now more particularly to the drawings, the terminal comprises a disk-like head 10 having a flat face 11 for engagement with one face of the web 13 of a rail. Projecting from the flat face 11 is a cylindrical boss 14 which is adapted to enter an opening 15 formed in the rail web for its reception. The head and boss are provided with an axial tapered opening 16 for the reception of a cylindro-conic spreader 17, the smaller end of which has an axial threaded extension 18 in which a nut 19 may be engaged. The nut 19 abuts the outer face 20 of the head and the

tapered bore of the head and boss has its larger end at the free end of the boss.

Projecting from one side of the head 10 is a neck 21 which is of stocky construction and relatively long. The free end of this neck is in the form of a socket 22 for the reception of the usual flexible bond cable 23. The head 10 and boss 14 are diametrically split upon a diameter bisecting the neck and this split is continued well into the neck and to a point 55 adjacent the inner end of the socket 22, as indicated at 24.

In the application of the bond, the boss 14 is inserted in the opening 15 after which the spreader 17 is inserted and tightened by means of the nut 19. This tightening causes the sections of the head and boss to spread with the result that the side walls of the boss very firmly engage with the walls of the opening 15 to establish an electrical connection therewith. Since the split permitting separation of the sections of the head is continued well into the neck, it follows that the amount of movement necessary at the terminal of the split to permit spreading and contraction of the bond when applied or removed will be very slight, so that the tendency to rupture of the fibers of metal is reduced to a minimum and a bond provided which is highly recoverable and which, at the same time, may be very readily applied to the rail. It will, of course, be obvious that other means of attaching the bond and cable 23 to the neck might be provided and I accordingly do not limit myself to the construction hereinbefore set forth except as hereinafter claimed.

I claim:

A rail bond terminal comprising a head having upon one side face thereof a boss, the head and boss having a tapered bore the larger end of which is disposed at the free end face of the boss, a spreading wedge adapted to extend through the bore and having associated therewith means engaging the opposite face of the head whereby it may be shifted and a

neck projecting from one side of the head and having means at its free end whereby a bond cable may be secured thereto, said head and boss being diametrically split by a slot extending well into the neck, the larger end of said spreading wedge being of a diameter less than the diameter of the opening with which the boss is adapted to coact, whereby said wedge element may be loosened and the head and boss contracted and withdrawn from one side of the rail.

10 In testimony whereof I hereunto affix my signature.

WILLIAM B. WARDROP.
